UNITED STATES PATENT OFFICE.

HERMANN HERDEGEN, OF STUTTGART, GERMANY.

TEMPORARY BINDER.

No. 911,396.

Specification of Letters Patent.

Patented Feb. 2, 1909.

Application filed March 16, 1908. Serial No. 421,523.

To all whom it may concern:

Be it known that I, HERMANN HERDEGEN, a citizen of the German Empire, and a resident of Stuttgart, in the State of Würtemberg, Germany, have invented certain new and useful Improvements in Temporary Binders, of which the following is a full, clear, and exact description, reference being had to the accompanying drawings, forming part of this specification.

My invention relates to improvements in temporary binders of the oscillating impaling prong variety. And the object of my improvements is to provide a binder of this class which has a considerable strength, so that the sheets are not so much subject to injury as in binders heretofore in use. For this purpose, the back of the binder which carries the prong mechanism is so constructed as to assume a box like form when the binder is closed, the side walls of which box, in the closed position of the binder, are perfectly stationary while they may be folded after unlocking their bracing elements. To effect this, the bars carrying the prongs are connected with each other by toggle joints.

For the purpose of illustrating the invention, I have shown two examples embodying the same in the accompanying drawings, 0 in which the same letters of reference have been used in all the views to indicate corresponding parts.

In said drawings—Figure 1, is a side view of the prong mechanism showing the parts in the closed position, Fig. 2, is a plan of Fig. 1, Fig. 3, is a view on an enlarged scale of the mechanism shown in Fig. 1, the parts being shown in their open position, Fig. 4, is a plan of a modification of the binder shown in Figs. 1 to 3, Fig. 5, is a cross-section of the binder shown in Fig. 4, showing a side view of the prong mechanism, Fig. 6, is a cross-section of the binder illustrated in Figs. 4 and 5, and showing the parts in the closed position of the binder, Fig. 7, is a similar cross-section showing the parts in the open position of the binder and the prong mechanism, and Fig. 8, is a similar cross-section showing the prongs in a semi-opened position.

Referring particularly to the example illustrated in Figs. 1 to 3, two narrow rigid folding members *b b* are attached to the back *a* of the binder, which members also have a folding connection with the cover boards *c c*.

To the upper edges of the folding members *b b* sheet metal strips *e e* are linked by pivots *d d*, which carry the circular prongs *f f* and bear against the inner surfaces of the folding members *c c*. The sheet metal strips *e e* are bent into Z-form, the shanks jointed to the folding members being adapted to bear against the latter, and the outer shanks being adapted to bear against each other, when the prongs are closed. At their lower ends 65 *e' e'*, they are connected with each other by a hinge *g*. In the closed position of the binder, the end portions *e' e'* of the strips *e e* bear against each other, and they are preferably held in the said position by means 70 of a spring catch *h*. For releasing the latter from its engagement with an aperture *m* provided in the strip portion *e'*, a lever *i* is provided.

The operation of the apparatus is as follows: In order to insert or remove a sheet the spring catch is disengaged, by means of the lever *i*, from the aperture provided in the strip *e'*, whereupon the folding members *b b* are folded outwards. Thereby, the hinge *g* is moved upwards, and the sheet metal strips *e e* are removed from the members *b b*, and the ends *e' e'* are separated from each other. Simultaneously, the prongs *f f* are telescoped out of engagement 85 with each other, until the space between their ends is sufficient to insert or remove the sheets. The ends of the prongs *f* are raised with the strips, and the sheets slide towards the joints *d d* and find a support 90 on the cover boards. As the distance of the ends of the prongs from the pivots *d d* is always the same, any tension within the holes of the sheets is avoided, so that the latter can not be torn.

From the above description, it will readily be understood, that the mechanism for holding the sheets is positively locked within the folding members by the locking mechanism *h* connecting the strips *e e*. The back 100 *a*, the folding members *b b* and the prong mechanism form a rigid structure, whereby a considerable rigidity is imparted to the binder. The reason for the said rigid connection of the parts of the binder lies in the fact, that the connection of the strips with each other and with the folding member is similar to that of a toggle joint which allows the folding members to be folded only if its side members *e e* are swung up. 110

- wards. The rigidity of the connection of the back of the binder and the folding members is obtained by the upper parts of the strips *e e* bearing against the members *b b* and, therefore, providing a brace between the latter and the back. On account of the said rigidity of their holding mechanism, the sheets are securely held in their positions.
- 10 The folding members or the back may be provided with springs tending to push the toggle joint upwards after disengaging the locking mechanism therefrom, whereby the prongs are automatically opened.
- 15 For opening or closing the toggle joint, I prefer to provide a lever rigidly connected with the said joint and having a handle or the like. In the example illustrated, in which a spring actuated catch is secured to one element of the toggle joint and arranged to engage an aperture provided in the other element, the lever has a spring action at its end where it is connected to the toggle joint, or it is pivotally supported thereon, so that it can be pressed downwards in order to disengage the spring catch from its opening. Instead of the arrangement shown, a lever may be mounted on the back, which lever, preferably through the intermediary of a roller, presses against the toggle joint.
- 20 In the example so far described, when opening the prongs, the parts of the toggle joint describe an angle of 90° , so that the time for moving the parts from one of their end positions into the opposite one is comparatively large. This will prove to be particularly inconvenient, where a plurality of sheets are to be filed at various places.
- 25 Now, in Figs. 4 to 8, I have shown an example of the binder in which the motion of the parts and therefore the time required for filing a sheet is abbreviated. As shown in the said figures, the prong mechanism is the same as that described before. The locking mechanism, however, is modified in this respect, that it can be thrown into operation not only in one of the end positions of the parts, but also in an intermediate position of the same, in which the prongs, though being closed, do not perfectly overlap. In the said position of the parts, the sheets impaled on the prongs must be moved a larger way than in the closed position. This increase of the way of the sheets, however, is advantageous, because the sheets are separated from one another to a larger extent and are but slightly moved towards one another when closing the prongs from their intermediate position. Therefore, the tearing effect exerted on the sheets when opening or closing the prongs for inserting or removing a sheet is decreased. In the example shown in the drawings the said effect is obtained by providing two locking posi-

tions, the spring catch or the locking lever having a plurality of locking abutments adapted to lock the prongs in different positions. As appears from Figs. 6 to 8, the spring catch *h* is provided with two ratchet teeth *o, p..* In Fig. 6, the innermost ratchet tooth *p* engages in the opening *m* of the co-operating strip *e*, whereby the prongs are perfectly closed. In Fig. 7, the prongs are entirely opened, and in Fig. 8 the outer ⁷⁵ ratchet tooth *o* of the spring catch engages in the opening of the strip *e*, so that the prongs are in their intermediate position.

By constructing the binder in the manner described, I obtain the following advantages: The sheets have a perfect support in every position, so that they are not liable to be torn. While opening, the binder is securely supported at whatever place a sheet is to be removed or inserted, whereby its use is rendered more convenient. On account of their reliable support the papers may be written upon while within the binder, without turning the back part relatively to the cover boards.

90 I claim:

1. In a letter file, the combination with a back of a pair of rigid folding members interposed between the back of the binder and its cover boards and having a folding engagement therewith, a toggle joint connecting the outer ends of said folding members and having its co-operating parts made in the form of a *Z* the inner shanks of which are adapted to bear against each other and the outer shanks of which are adapted to bear against the folding members when the prongs are in their closed position, a pair of impaling prongs mounted on the members of said toggle joints, and means to lock the members of the toggle joint.

2. In a letter file, the combination with a back, of a pair of rigid folding members interposed between the back of the binder and its cover boards and having a folding engagement therewith, a toggle joint connecting the outer ends of said folding members and having its co-operating parts made in the form of a *Z* the inner shanks of which are adapted to bear against each other and the outer shanks of which are adapted to bear against the folding members when the prongs are in their closed position, a pair of impaling prongs mounted on the members of said toggle joints, means to lock the members of the toggle joint, and a lever mounted on one of the members of said toggle joint and adapted to disengage the locking mechanism therefrom and to open the toggle joint.

3. In a letter file, the combination with a back, of a pair of rigid folding members interposed between the back of the binder and its cover boards and having a folding engagement therewith, a toggle joint connect-

125

130

ing the outer ends of said folding members and having its coöperating parts made in the form of a Z the inner shanks of which are adapted to bear against each other and 5 the outer shanks of which are adapted to bear against the folding members when the prongs are in their closed position, a pair of impaling prongs mounted on the members of said toggle joints, and means to lock

the members of the toggle joints in different positions.

In testimony whereof I affix my signature in presence of two witnesses.

HERMANN HERDEGEN.
